Primary Examiner — Paula Allen Greene(74) *Attorney, Agent, or Firm* — Sanchelima & Associates, P.A.; Jesus Sanchelima; Christian Sanchelima(57) **CLAIM**

The ornamental design for speaker basket with ring, as shown and described.

DESCRIPTION

FIG. 1 is an isometric view of a speaker basket with ring showing my new design;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof; and,

FIG. 8 is an isometric view thereof showing my design with the ring separated from the basket.
